UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

STOKER FURNACE.

Application filed May 31, 1923. Serial No. 642,386.

This invention relates to furnaces equipped with mechanical stokers such as endless chain grates and provided with vertical air ducts at the sides of the grate for supplying the active grate surface with a draft delivered to the same from below and on opposite sides of the grate.

One object of my invention is to provide a construction whereby either natural or forced draft may be delivered to the grate through these ducts and thus regulate the furnace to the kind of fuel being burned.

Another object of my invention is to provide dampers for both drafts and to operate them simultaneously so that on opening the forced draft dampers the natural draft ones will be closed and vice versa.

A further object of the invention is to provide an improved form of damper operating means.

The invention consists further in the matters hereinafter described and more particularly set forth in the appended claims.

In the accompanying drawings—

Fig. 1 is a longitudinal vertical sectional view of a chain grate stoker embodying the features of my invention;

Fig. 2 is a horizontal sectional view taken on line 2—2 of Fig. 1;

Fig. 3 is an enlarged transverse vertical sectional view taken on line 3—3 of Fig. 1;

Fig. 4 is a view showing details of the lower shoe and its connection with the associated cross-member; and

Fig. 5 is a view of one of the forks and its bar, to be hereinafter described.

In the drawings, 1 indicates a chain grate stoker having upper and lower leads 2, 3. Said grate 1 extends into the combustion chamber of the furnace through the front wall of the furnace setting and has its rear or tail end terminating short of the bridge wall 4 to provide a vertical ash discharge passage as in structures of this general kind. At the front wall is a fuel hopper 5 through which fresh or green fuel is fed on the upper lead 2 to be carried thereby in a layer for consumption, as understood in this art.

The grate 1 extends horizontally between the side walls 6, 6 of the setting, as shown in Fig. 3, and these walls each include a plurality of upright metal stools 7, 7 at op-

posite sides of the grate. The stools 7, 7 in each wall are laterally spaced apart, as shown in Fig. 2, and as there illustrated the furnace has six stools 7 in each side wall. The stools 7 in one wall are aligned with those in the opposite wall, and in both the stools rest on the foundation 8 of the furnace setting.

The stools 7, 7 support the side walls 6, 6 and have extending between them at their upper ends channel bars 9, 9 for this purpose, as shown in Fig. 3. Extending between the stools 7 at each side of the grate are metal shells or walls 10, 10. These are secured to the stools and form therewith a plurality of vertical air ducts 11, 11 on opposite sides of the grate. These ducts open at their upper ends into the space between the grate leads 2, 3 and at their lower ends into a main air supply passage 12, arranged in the foundation below the lower lead 3 and between the air ducts 11, as shown.

The space between the grate leads 2, 3 is divided into a plurality of compartments 13, 13 equal in number to the vertical ducts at one side of the grate and communicating with them at both sides of the grate. These compartments are made by I-beams 14, 14 extending between and secured to the stools 7, 7. The beams support skids 15 under the upper lead 2 and support the latter. Along the beams 14 are shoes 16, 17. These bear against the grate leads and provide air seals for the compartments 13. The lower lead is supported by beams 18 and skids 19. The former extend between and are secured to the stools 7. Shoes 20 bear against the under surface of the lower lead 3 at said beams. Plates 21 extend between the lower beams 18 to close the compartments from the main supply passage 12. The foregoing structure is more fully described and is claimed in my co-pending application Serial No. 642,385, filed May 31, 1923.

Dampers 22 control the forced draft and dampers 23 the natural draft. The ones 22 are hinged to bars 24 supported by the stools 7. The dampers 23 co-operate with open frames 25 in the walls 10. Each pair of opposed ducts 11 has a set of four dampers, the ones 22 for forced draft from the passage 12 and the others for the frames 25 for natural draft. The dampers 23 carry frames 26 to guide them into the frames 25.

To open and close each set of dampers, I provide an endwise movable bar 27, horizontally arranged under the lower lead 3 and extending through the side plates 10, 10 at both sides of the furnace. On the bar 27 at one side of the furnace is a fixed pin 28. This projects outward on opposite sides of the bar and is arranged back of an upright forked lug 29 on the associated damper plate 22. When the bar 27 is moved endwise toward the right as viewed in Fig. 3, the pin 28 is brought into contact with the lug 29 and the damper plate 22 swung open, as shown in said figure. When moved away from the lug the damper plate closes by gravity as shown in dotted lines in Fig. 3. To open and close the opposite damper 22 simultaneously with the one just described, a link 30 connects said damper with the bar 27, as shown in Fig. 3.

For each set of natural draft dampers 23, I provide the following construction. Extending horizontally through the stools 7, 7 on opposite sides of the stoker are shafts 31. These are located in the air ducts 11 to the rear of the associated dampers 23 and slightly below the same. Each damper 23 is connected by an arm 32 with its shaft 31. Said arms 32 are pivoted at their upper and lower ends to the said damper and shaft, respectively, so that the damper may be opened and closed by moving said arms. To do this, the arms of each damper are actuated through the rod 27. Fixed to said arms are downwardly and inwardly extending members 33, 34, the former at one side of the grate and being in the shape of a fork to straddle the rod 27, as shown in Fig. 5.

The member 34 at the opposite side is in the form of a link pivoted at its upper end to the associated damper arms 32, as shown in Fig. 3.

The link 34 extends to the rod 27 and has its lower end between pins 35, 35 fixed on said rod 27. Said link 34 has a slot 36 on its under side to receive the outer pin 35. This pin is thus between the shoulders formed by the ends of said slot. The other pin 35 is the inner one and holds the outer one in said slot. At the fork 33, the rod 27 carries a fixed collar 37 having a forwardly and downwardly inclined lug 38. The collar has fixed projections 39 on opposite sides and the lug has pins 40, as shown in Figs. 3 and 5. The fork 33 operates between these parts 39 and 40, and by them the associated dampers 23 are opened and closed on moving the rod 27.

For operating said rod there is a hand lever 41 at one end thereof. Said lever 41 is at one side of the furnace in the space between two stools 7 and outside of the associated shell or wall 10. This makes the lever accessible from the exterior of the stoker. Said lever is mounted on a rock

shaft 42 journaled in the stools 7, 7 at its side of the stoker.

When the rod 27 is moved toward the left, the forced draft dampers 22 are closed and the natural draft ones 23 are opened. The reverse happens when the rod is moved in the opposite direction. In opening the left-hand damper 23, the upper lugs 39 engage the fork 33 and push on it to open said damper. The fork 33 passes into the space between the lugs and pins 40 and comes to rest against the latter. In closing, the pins 40 raise the fork, as is apparent.

In opening the right-hand damper 23, the outer pin 35 pulls inward on the link 34 and opens said damper. On swinging open, the link passes through the pins 35 until stopped by the upper shoulder coming to rest against the outer pin. In closing, the force is exerted on the link 34 by the outer pin on the upper shoulder until the damper passes the center of its pivotal movement whereupon gravity moves the damper the balance of the way closed. This raises the link 34 and brings the lower shoulder against the outer pin 35 as before.

The stools 7 make provision for the natural draft dampers 23, and thus allow them to be used with the forced draft dampers 22. This has the advantage of working the furnace on either forced or natural draft and thus allows regulating the furnace to best burn the kind of fuel being handled. Manifestly, it gives the stoker a wide range of fuels. For each set of opposed ducts 11, 11 are natural and forced draft dampers. Each set of dampers has its operating rod 27. These are operable independently of each other. This allows one or more of the compartments 13 to be supplied with forced draft while the others are under natural draft. The result is that the supply of draft to grate areas over the various compartments 13 may be regulated. This allows adjusting the draft over substantially the entire area of the grate to meet the burning qualities of the fuel being used.

The shoes 20 are pivoted to the members 14 as follows: Secured to each member 14 to the rear of the shoes therefor are brackets 43. These extend below said member, as shown in Fig. 4. There are two brackets 43 for each shoe and links 44 pivotally connect the shoes with their brackets. The lower ends of these links extend into the sockets 45 on the shoes. To keep closed the space between each row of shoes and their members 14, I provide plates 46, one for each shoe. Said plates 46 are hinged on the front side of their members 14 and extend to and overlap upright ribs 47 on the shoes, as shown. The hinged connection for each plate 46 is clearly shown in Fig. 4. There it will be observed that the plate has a number of upright lugs 48 pivoted be-

tween ears on brackets 49 secured to the members 14.

While I have shown and described herein in detail a furnace structure embodying the features of my invention, it is of course to be understood that the details of construction and arrangement of parts may be variously changed and modified without departing from the spirit and scope of my invention.

10 I claim as my invention:

1. In a furnace, the combination with a grate, of an air duct on one side of said grate for supplying draft thereto, said duct having a natural draft opening in its wall,

15 means for delivering forced draft to said duct, pivotally mounted dampers, one for said opening and the other for controlling the supply of forced draft to said duct, and means common to both dampers for opening one when closing the other.

2. In a furnace, the combination of a grate, air ducts on opposite sides of the grate for supplying draft thereto, a set of forced draft dampers and a set of natural

25 draft dampers for said ducts, and means for operating said dampers including an endwise movable rod, a link connecting one forced draft damper with said rod, a lug and a pin connecting the other forced draft damper with said rod, and a fork and a slotted link with co-operating pins respectively connecting the natural draft dampers with said rod.

3. In a furnace, the combination of an endless chain grate, having upper and lower leads, laterally spaced upright stools on opposite sides of said grate, members extending transversely across the space between said leads and connected with the 40 stools on opposite sides of the grate for dividing said space into a plurality of compartments, walls extending between the stools at the sides of the grate and forming with said stools air ducts opening into said compartments for supplying draft thereto, means beneath the lower lead for supplying forced draft to said ducts, dampers for controlling the supply of forced draft to said ducts, additional dampers in 45 said walls for supplying natural draft to said ducts, and means for actuating simultaneously the forced and natural draft dampers of each set of opposed ducts by

closing one set of dampers and opening the other set.

4. In a furnace, the combination of an endless chain grate having upper and lower leads, laterally spaced upright stools on opposite sides of said grate, members extending transversely across the space between 55 said leads and connected with the stools on opposite sides of the grate for dividing said space into a plurality of compartments, walls extending between the stools at the sides of the grate and forming with said stools on 60 opposite sides of the grate air ducts opening into said compartments, means beneath the lower lead for supplying forced draft to said ducts, dampers for controlling the supply of forced draft to said ducts, additional 65 dampers in said walls for supplying natural draft to said ducts, and means in the spaces between the stools at one side of the grate for opening and closing the forced and natural draft dampers on both sides of the 70 grate.

5. In a furnace, the combination with a grate, of an air duct at one side of the grate for supplying draft thereto, said duct having a draft opening in its wall, a damper 80 plate for said opening, a shaft in said duct, an arm fixed to said shaft and pivotally connected with said plate, a yoke on the shaft, an endwise movable rod passing said duct and yoke, and spaced lugs carried by 85 said rod to receive between them the legs of the yoke for opening or closing said plate through said rod.

6. In a furnace, the combination with a grate, of an air duct at one side of the 90 grate for supplying draft thereto, said duct having a draft opening in its wall, a damper plate for said opening, a shaft in said duct, an arm fixed to said shaft and pivotally connected with said plate, an endwise mov- 95 able rod extending through said duct and having spaced lugs thereon, and a link piv- oted at one end to said arm and having its other end slotted and between said lugs for opening and closing said plate through 100 said rod.

In testimony that I claim the foregoing as my invention, I affix my signature this 28th day of May, A. D. 1923.

HERMAN A. POPPENHUSEN.
